US00D580912S

(12) **United States Design Patent**
Andre et al.

(10) **Patent No.:** US D580,912 S
(45) **Date of Patent:** ** Nov. 18, 2008

(54) **SPEAKER UNIT**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, San Francisco, CA (US); **Matthew Dean Rohrbach**, San Francisco, CA (US); **Douglas B. Satzger**, Menlo Park, CA (US); **Calvin Q. Seid**, Palo Alto, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/296,896**

(22) Filed: **Oct. 30, 2007**

(57) **CLAIM**

We claim the ornamental design for an speaker unit, substantially as shown and described.

DESCRIPTION

FIG. 1 is a front perspective view of a speaker unit in accordance with the present invention;

FIG. 2 is a rear perspective view thereof;

FIG. 3 is a front view thereof;

FIG. 4 is a rear view thereof;

FIG. 5 is a top view thereof;

FIG. 6 is bottom view thereof;

FIG. 7 is a right side view thereof;

FIG. 8 is a left side view thereof; and,

FIG. 9 is a front view thereof with the speaker cover removed.

The broken lines illustrating the speaker unit are included for the purpose of illustrating environmental structure only and form no part of the claimed design.

1 Claim, 6 Drawing Sheets
